WO WO2016089803 6/2016

Primary Examiner — Wan Laymon*Assistant Examiner* — Clint A Samuel(74) *Attorney, Agent, or Firm* — Lawrence Cruz, Esq.; Ryan, Mason & Lewis, LLP(57) **CLAIM**

The ornamental design for a hair brush, as shown and described.

DESCRIPTION

FIG. 1 is a perspective view of the hair brush in accordance with the principles of the present disclosure illustrating, in broken lines, a container having dry shampoo mounted relative to the hair brush;

FIG. 2 is a right side elevation view of the hair brush of FIG. 1, the left side elevation view being a mirror image thereof; FIG. 3 is a top plan view of the hair brush of FIG. 1; FIG. 4 is a bottom plan view of the hair brush of FIG. 1; FIG. 5 is a front axial view of the hair brush of FIG. 1; and, FIG. 6 is a rear axial view of the hair brush of FIG. 1. The broken lines shown indicate unclaimed portions of the article and form no part of the claimed design.

1 Claim, 5 Drawing Sheets(56)
